UNITED STATES PATENT OFFICE

140,875

DESIGN FOR A HELICOPTER MOTORCYCLE

Daniel E. Gumb, Milwaukee, Wis.

Application November 13, 1944, Serial No. 116,305

Term of patent 14 years

(Cl. D71—1)

To all whom it may concern:

Be it known that I, Daniel E. Gumb, a citizen of the United States and resident of Milwaukee, in the county of Milwaukee and State of Wisconsin, have invented a new, original, and ornamental Design for a Helicopter Motorcycle, of which the following is a specification, reference being had to the accompanying drawing, forming part thereof.

This application is a continuation-in-part of my copending application, Serial No. D-111,430, filed October 20, 1943.

Figure 1 is a side elevational view of a helicopter motorcycle showing my new design.

Figure 2 is a front elevational view thereof.
Figure 3 is a rear elevational view of the helicopter motorcycle.

Figure 4 is a top plan view thereof.
The opposite side of the helicopter motorcycle is the same as the side shown in Figure 1, with the exception that the door is omitted.

In Figures 2, 3 and 4 the propellers have been broken away for convenience of illustration.

I claim:

The ornamental design for a helicopter motorcycle, as shown and described.

DANIEL E. GUMB.
